TYPE CASTING AND SETTING MACHINE

Frederic Devèze, Paris, France

Application July 16, 1936, Serial No. 90,964
In France July 19, 1935

13 Claims. (Cl. 199—74)

This invention relates to improvements in machines for casting and setting movable type, such as that known under the name of "Rototype", described in the United States Patents Nos. 1,195,-
5 742 and 1,553,190.

These machines have usually been provided up to now with a frame carrying matrix blocks sliding on the front of the machine by means of a crank and worm. For changing the type, the operator is compelled to unlock the frame and to turn the crank until the desired block is at the level of the mould.

On the contrary, owing to the matrix-carrying frame according to the invention, this change can be effected without any other intervention, on the part of the operator than the simple depression of two keys on the keyboard. He thus marks, for instance by two pawls of the main pawl-carrying drum, that the change of type must take place at the time these pawls, lifted by the keyboard, come opposite the clutch determining the movement effecting the change of blocks. This change takes place automatically.

During type-setting, the block which is opposite the mould receives, as is well known, two movements: a movement of rotation, and a reciprocating movement. The action of the pawl actuated by the first key depressed stops the reciprocating movement of this block when the latter is at one end of its stroke, for instance at the left. It is only in this position that it can be moved, through a quarter of a revolution, if the blocks are four in number.

It is the action of the pawl actuated by the second key which causes this replacement. The block thus placed in front of the mould immediately resumes its reciprocating movement: the type-setting is not delayed.

It is known moreover that the "Rototype" machine comprises an operating lever which, by acting on the members with which it is in contact, allows of obtaining:

- (1) The measurement of the gap to be filled up by the spaces in a line recorded on the drum;
  - 45 (2) The distribution of this gap according to the number of spaces contained in said line;
  - (3) The transmission of this value of distribution;
  - 50 (4) The resetting to zero of the counter for the thicknesses of the letters;
  - (5) The resetting to zero of the counter for the spaces;
  - (6) The recording on the drum of the end of the line of type set.
- 55 The raising and lowering of this lever was

effected up to now by hand and the actuation of said lever, which required an effort on the part of the operator, was sometimes unsatisfactory.

On the contrary, according to the invention, this actuation causing the six functions mentioned above, is automatically obtained by simple depression, by means of the finger, of a key of the keyboard of the machine.

In other type casting and setting machines, the widths of the letters depressed on the keyboard are recorded on a counter, provided with a rotating drum, which indicates, at the end of the line, a plurality of digits. For obtaining justification, the operator must depress the keys corresponding to these digits, taking care not to make a mistake. In that respect, the invention reduces the work of the operator to the depression of a single key, always the same, without any reading of digits or depression of other keys being necessary.

Moreover, it is known that the "Rototype" machine is provided with a control and so-called repetition lever, which allows the operator to move the drum forward to the extent of one division or in a continuous manner, independently of the keyboard.

When the operator, for instance, comes to the end of an article, or, when at the end of the day, he desires to terminate the casting of the lines recorded on the drum, he must then, according to the known device, actuate the repetition lever as many times as there remain recorded letters to be cast from the time he no longer sets new type on the keyboard.

The same actuations would be necessary when casting type for filling cases.

The present improvements eliminate this obligation. They allow of automatically casting the recorded lines, for instance at the end of an article or at the end of the day, by actuating only once the repetition lever.

Finally, up to now the composing of tables on the "Rototype" machine is effected by hand in separate columns which are subsequently assembled on the press bed or press-stone. On the "Rototype" machine this can thus be effected without any difficulty by composing column by column with the required justification and by subsequently assembling them.

The device according to the invention avoids the manipulation and manual assemblage of the columns, thus accelerating the composing.

Moreover, the present device can, for the composing of tables, be very rapidly placed in posi-

5

55

tion and removed with the same rapidity for passing to the normal composing without tables.

When the said device is applied to the "Rototype" machine, profit is of course derived from the advantages of the latter; in particular, it is possible to use in one and the same table different kinds of type.

An embodiment of the improvements according to the invention will now be described, by way of example, with reference to the accompanying drawings, in which:

Fig. 15 is a plan view.

Fig. 16 is a detail side view.

Fig. 17 is a plan view corresponding to Fig. 16.

The matrix blocks, in the example four in number, are placed between two discs 198 arranged in the matrix-carrying frame 199. At the center, between the four blocks 201 is arranged a square shaft 200, serving as a bearing for the blocks during the casting of the type.

35 Said shaft 200 also holds both discs 198 at the required distance apart.

Near its right-hand end, the square shaft 200 carries a socket 202 which holds apart two outer discs, one of which, 203, serves to move the blocks forward through a quarter of a revolution, and the other, 213, serves to lock the discs 198 and, consequently, the corresponding matrix block in the exact position in front of the mould.

40 The frame 199 is made in two parts: a lower part, which can be inserted between two slides 204 secured on the frame of the machine, the other, 199^a, forming a cover for both discs 198. This cover 199^a is secured on the lower part by four screws; both cylindrical discs 198 rotate without play between the lower part and the cover. On the other hand, said cover is provided, at its upper part, with a handle in order that the whole may be easily inserted and removed behind the slides 204.

45 A crank 205, connected to a shaft 48, effects exactly one revolution when the pawl, actuated by the second depressed key, acts on the corresponding clutch member, for instance in the manner described in the United States Patent No. 1,553,190. The crank pin 206 of crank 205 is fitted in a slide-block 206^a moving in a slide 207^a formed in a large lever 207. The movement of rotation of crank 205 causes lever 207 to rock.

50 In Fig. 2, the levers 207-209 and 211 are shown in their position of rest, but, in Fig. 1, the lever 211 is rotated forward to the extent of 90° in order that its pivot pin 216 and the pawl 212 should be visible.

55 In the first phase of the movement of rotation of crank 205, the lever 207 is pushed towards the right relatively to the vertical in the direction of the arrow.

60 It encounters the stud 208 of a lever 209 mounted about the pivot pin 210 and releases the conical nose 209^a of this lever from a notch *a*,

also of conical shape for ensuring the exact position and provided in the disc 213. At the same time, this lever 207 moves towards the right, by its forked end, a lever 211 arranged between the discs 203 and 213 until the pawl 212 of this lever 5 211, mounted about the pivot pin 216, has reached the recess *b*¹ formed in the disc 203 and enters said recess. At this moment, the crank 205 has moved through a quarter of a revolution and has moved the lever 207 to its extreme right- 10 hand position.

By continuing its movement of rotation, the crank 205 begins to push the lever 207 to the left, towards its starting position. As the pawl 212 is engaged in the recess *b*¹ of disc 203, the 15 latter and with it all the movable portion of the frame, that is to say the discs 198, central shaft 200, the four matrix blocks 201 with their shafts, the four pinions 214 and drums 215, is moved forward, in the direction indicated by an 20 arrow, to the extent of 90°.

The matrix block which was previously located in front of the mould is therefore replaced by the next block, at 90° from the preceding one. The crank 205, continuing its movement of rotation towards the starting position, restores the lever 207 to the position shown in Fig. 2, and stops.

When leaving its extreme right-hand position for returning towards the left, the lever 207 30 moves away from the stud 208 of lever 209, which, under the action of a spring not shown in the drawings, moves the nose 209^a towards the periphery of disc 213 which is rotating.

This nose exerts a certain pressure on the disc 35 213, which pressure, far from being prejudicial to the operation, has the effect of reducing the vis viva generated by the rapid movement of the whole.

At the end of the movement of lever 207 towards the left, the next notch *a* comes in front of the nose 209^a of lever 209 which, pushed by its spring, immediately enters therein and thus ensures the exact position of the fresh block relatively to the mould.

45 This movement of rotation through a quarter of a revolution rapidly takes place and generates, owing to the weight of the whole, a relatively important vis viva which, at the end of this movement, would cause a shock. For avoiding 50 this shock, the apparatus is provided with two levers 217 and 218 each mounted at one end of a shaft 219 (Figs. 2 and 3).

The lever 217 is arranged between the lever 209 and the frame 199; when the lever 209 is pushed 55 by lever 207 in the direction of the arrow, it acts, through a stud 208^a, on lever 217 and moves it through a certain angle.

The lever 217 being rigid with the shaft 219 and lever 218, it therefore moves the end of the 60 latter away from the periphery of a disc 220. The latter is secured, by screws, on the left-hand disc 198 and, consequently, rotates with all the movable portion. The disc 220 is provided, on its periphery, with four notches in which the lever 65 218 can enter. These notches are similar to the notches *b* formed in disc 203; the lever 218 enters therein before the rotation has completely stopped. The levers 217 and 218 are urged towards the center by a spring (not shown); the 70 end of lever 218 therefore enters one of the elongated notches of disc 220 as soon as it comes opposite the end of said lever.

The locations and the manner in which the disc 220, lever 218 and its shaft 219 are secured 75

have been so chosen as to most efficiently absorb the shock which occurs at the end of the movement, and the whole operates perfectly.

The frame 199 carries four matrix blocks 201, two only of which are shown on the drawings, Fig. 1. Each of the blocks 201 rotates, with its drum 215 and its pinion 214 in bearings provided on the discs 198; they can horizontally move on the shafts 221 under the action of a lever 222 which imparts to the block opposite the same a reciprocating movement.

It is therefore only the block which is opposite the mould which receives the two movements. The three other blocks are held stationary in the position determined by the rib 223 of frame 199 which enters their collar, that is to say near their left-hand end, and prevents them from horizontally moving.

The change of a block is obtained as follows: The change is recorded on two pawls of the drum; the first acts on the device stopping the reciprocating movement; this reciprocating movement is stopped when the block 201 is in its extreme left-hand position, as shown in Fig. 1. The lever 222 therefore also stops in the same position. This occurs for a certain advance of the drum. Upon the next advance, the pawl corresponding to the second key depressed, acts on the clutch of crank 205. The crank 205, by its crank pin 206, actuates the lever 207 which releases the nose 208 of lever 209 from the disc 213. The lever 211, through its pawl 212, causes the disc 203 to rotate forward through a quarter of a revolution and with it the matrix blocks.

The block 201 which was located in front of the mould, therefore moves down through a quarter of a revolution and is replaced by the second block, or by the third or the fourth block if necessary. Of course, each new change must be recorded beforehand on the pawls by action on the keyboard. The movement of rotation has not been stopped during the change; the outgoing block has disengaged from the driving pinion, and the next pinion has engaged with this driving pinion quite as easily.

The reciprocating movement has still to be started. For that purpose, the disc 203 carries, on its outer face, four projections *c* (Figs. 1 and 2) spaced apart to the extent of 90°. In the path followed by these projections is arranged a clutch lever which, pushed back at the end of the movement of rotation of disc 203, couples the lever 222 and thus causes block 201 to resume its longitudinal movement. The composing can therefore be immediately continued, without loss of time.

Referring to Figs. 6 to 8, it will be seen that an eccentric 160 is mounted on a stub shaft 161 secured in the support of the keyboard 10, the latter being carried by the frame 1 of the machine. The stub shaft 161 is moreover provided with a socket 162 carrying, on one side, a coupling ring 162^a and, on the other side, a sprocket wheel 162^b. This sprocket wheel is actuated from a pulley of the composing stick and continuously rotates in a counterclockwise direction.

On the other hand, the eccentric 160 is held in the position shown in Fig. 7 by means of a roller 163 mounted at the end of a lever 164 and extending in a small notch of this eccentric; the arm of the lever 164 carrying the roller 163 is, for that purpose, loaded with a weight 165.

About the pivot pin 167 is mounted another lever 166, the left-hand end of which, of wedge shape, rests on the coupling ring 162^a; this lever

166 thus holds in disengaged position a movable key 168 similar to that designated by reference number 36 in said United States Patent No. 1,553,190.

In Fig. 7, the lever 166 is shown in its position of rest; its right-hand end carrying a key 166^a is in normal position; this key can be depressed by simple pressure of a finger.

The second arm of lever 164 is connected, by a connecting rod 164^a, to the lever 123 provided with a handle and which, up to now, at the end of the recording of each line, had to be released by hand, lifted, lowered and hooked on again. It is these movements which are rendered unnecessary by the present device which also allows of dispensing with the depression of a key for marking on the drum the end and the beginning of the type line set.

At the end of a line formed on the keyboard and recorded on the pawls 5 of drum 4, the operator depresses the key 166^a of lever 166 and thus lifts the other end of said lever, thus releasing the movable key 168 which immediately couples the rotating socket 162 to the eccentric 160. The latter, after having effected a revolution in the direction of the arrow, moves the key 168 in front of lever 166 which, by its wedge shaped incline, pushes it back and disconnects this key 168 from the socket 162 which continues to rotate.

During the rotation of the eccentric 160, the lever 164, pulled by the weight 165, pivots; its right-hand arm rises, pushing before it the connecting rod 164^a connected to lever 123, lifts the latter to the required level and lowers it immediately after.

By this movement of lever 123, effected mechanically, the effects indicated above are obtained, viz:

(1) The measurement of the gap to be filled up by the spaces in the line;

(2) The distribution of this gap on the number of spaces contained in this line;

(3) The transmission of the value thus obtained;

(4) The resetting to zero of the counter for the thicknesses of the letters;

(5) The resetting to zero of the counter for the spaces;

(6) The depression of the key for recording the end of the line.

When the lever 123 rises, it releases, by its foot 123^a (Fig. 6) the lever 172 which was held in the position shown in Fig. 6. This lever 172, urged by a spring 172^a, rocks towards the right, until 55 its flexible end comes behind curved end 169^a of a blade 169. The latter is connected to a three arm lever 170 urged by a spring 170^a.

Its arm 170^b extends a certain distance beyond its point of attachment to the blade 169; when 60 the cam 160 returns towards the position shown in Fig. 6, the blade 169 is pushed towards the left; when this movement takes place, the arm 170^b comes in contact with a lever 173 and pushes it.

The arm 170^c of lever 170 is provided with a pivoted pawl 170^d which, by lifting, engages with the clutch lever 152 for the rotation of the drum.

The third arm 170^e of lever 170 acts on the key 19^a which actuates a pawl of the drum which 70 marks the end of the line and causes the starting movement towards the galley of the type line cast.

The end of arm 170^b, during its movement towards the left, comes in contact with a lever 75

173 secured on one of the pillars or uprights of the thickness counter 18 and pushes it. The forked end of lever 173 engages with a projection 173^a of a horizontal blade 174, and pushes the latter horizontally towards the right until it comes with its notch 174^a below the nose 175^a of a lever 175, which holds it stationary in this position.

In the position shown in Fig. 1, the descent 10 of the nose 175^a into the notch 174^a is impossible, the lever 175 being held in its position by the central rod 81 of the thickness counter 18; at the end of the type line composed, the central rod 81 is moved towards the left to an extent corresponding to the length of the line, and nothing prevents the engagement of the nose 175^a with the notch 174^a.

The blade 174 being thus held stationary, the return of the central rod 81, and of the index 20 95 it carries at its left-hand end, to its starting position is thus facilitated.

To the index 95 is attached a small chain (not shown) loaded with a weight, which after each type line composed, causes the central rod of the 25 counter, with its index, to return towards the right to its starting position.

During the return of the central rod 81, and for giving it sufficient time to accomplish this movement, the blade 174 is held, by the nose of lever 30 175, in its right-hand position, but, immediately the central rod 81 has reached the end of its movement towards the right, its end strikes against the lever 175, lifts it to the position shown, and the nose 175^a releases from the notch 35 174^a of blade 174 which, under the action of a spring, returns to the left, the lever 173 returning to its original position.

As the blade 174 is held stationary in its locked 40 position by the nose 175^a, the central rod 81 is held free for its return to the right owing to its curved left-hand end 174^b which acts on lever 83; the latter is provided with a left-handed screw which clamps and loosens the central rod for stopping it or for releasing it.

In the locked position of blade 174, its end 174^b 45 holds the lever 83 in the position in which the screw is loosened; the central rod 81 is free to slide and, consequently, to return without hindrance to its original position. The blade 174 released by the lever 175, releases in its turn the lever 83, the screw of which locks again the central rod 81.

A device for correcting the position of the pawls 5 of drum 4 is also provided. This device is arranged on the left-hand side of the machine 55 (Fig. 6), and is composed of a flexible shutter 176 mounted on a pin 176^a supported by the two walls of the support of the composing-stick. This shutter has a width corresponding to the depth 60 of the drum; it engages with all the pawls 5 passing in front of it and completely opens those which would not be sufficiently opened by the blades of the keyboard. On the pivot pin of the shutter is mounted a lever 177 which, under the 65 action of a spring, holds the shutter in position on the paths followed by the pawls. The suitably projecting pawls push back the shutter 176; those which do not project to a sufficient distance are raised and no longer risk being accidentally withdrawn before reaching the right-hand side of the keyboard. Errors are thus avoided which might be caused in the composing by missing or non-cast type owing to the premature withdrawal of pawls 5.

75 Referring to Figs. 9 to 12, it will be seen that

178 designates a cam shaft which, by rotating through a revolution, controls the casting and composing or setting of a type. A round rod 182 is arranged between the supports 180^a and 181, parallel to the cam shaft 178, and this rod 182 5 is capable of rotating; said rod 182 carries, near its left-hand end, two levers 183 and 184 rigid therewith, and, near its right-hand end, it carries a lever 185.

This lever 185 is connected, by a link 186, to a 10 lever 187 secured to the end of a rod 188. The rod 188 is carried by supports 189 and 190 on the right-hand side of the machine, at right angles to rod 182. On the other end of rod 188, on the front of the machine, is secured a lever 191 the 15 left-hand end of which extends under the repetition lever 152.

The main cam shaft 178 rotates in the direction of the arrow traced on the small hand wheel 192 (Fig. 9). This cam shaft effects a single revolution and stops, owing to the provision of a clutch, known per se, controlled by levers 62—63 (Fig. 9). The latter are actuated by the pawls 5 of drum 4.

Every time the drum 4 moves forward to the 25 extent of one division in the direction indicated by the arrow, two of the pawls 5, if there are any projecting pawls in the series, come in contact with two of the corresponding levers 62 and 63 and slightly lift them; the movement is transmitted to levers 65—66 which, on the one hand, cause the movement of rotation and of translation of the matrix block to stop and, on the other hand, determine immediate engagement of the cam shaft 178. 35

During ordinary composing, it is the operator who by depressing the keys of the keyboard causes the drum to move forward. When the composing is finished, several lines recorded have still to be cast. Up to now, the operator was compelled to lift the repetition lever 152 as many times as there were type to be cast. Usually, their number amounts to about one hundred. It was therefore necessary to lift the lever 152 a considerable number of times. By means of the 40 present device, this operation is automatically effected.

For that purpose, the operator simply releases the lever 191 and moves it to the position shown in Fig. 10, in which its end is placed under the lever 152. By lifting the latter only once, the operator starts the drum 4, the forward movement of which causes cam shaft 178 to be thrown in gear. During the second half of the revolution of shaft 178, a roller 193, secured on a cam 194 55 (Fig. 10), comes in engagement with the lever 184 and lifts it; the movement is transmitted by rod 182, lever 185, link 186 and lever 187 to the rod 188 and lever 191, and the latter being placed under the repetition lever 152, therefore lifts it 60 at every revolution of the cam shaft, this causing the forward movement of the drum 4, resulting in the cam shaft being again thrown in gear, and so on up to the end of the line.

After the last revolution of the cam shaft, that 65 is to say when the last letter of the line has been cast, the line thus finished is pushed into the composing stick. At this moment, the mechanism 180 of the composing stick will enter in action, for causing the engagement of the drum 70 to the following line.

The cams and levers of the composing stick 180 are arranged on the left-hand side of the machine and, as is well known, transport the cast type line to the galley immediately after the last 75

letter has been cast, through the action of a particular pawl of drum 4 indicating that a line has started. At the end of this movement, the lever 179 of the mechanism of the composing stick 5 180 acts on the lever 183 secured on the rod 182 which transmits the movement to the repetition lever 152 and causes the drum 4 to move forward.

By this forward movement, the next pair of pawls 5, arranged in the drum, causes, as described above, the engagement of the cam shaft which subsequently automatically causes, after each letter cast, the engagement for the next letter, and this to the last letter of the line. The starting of the line for the composing stick again 10 actuates the clutch of the cam shaft and determines the casting of another line, and so on.

It will be seen that each revolution of the cam shaft 178 would cause the lifting of lever 185 and of all those secured on the rods 182 and 188. 20 Now this is unnecessary and undesirable during ordinary composing in which the operator himself controls the engagement of the drum by depressing keys.

During this time, according to the invention, 25 the mechanism previously described is rendered inoperative. For that purpose, the rod 188 terminates in a knob 195 within reach of the operator. Moreover, the lever 191 carries, near its right-hand end, a hook 196 secured for instance 30 by two screws (Figs. 11 and 12). Between the support 189 and the lever 187 is interposed a spring 197 which holds the rod 188, its levers and the knob 195 in the position shown in Figs. 9 and 11.

35 This position is that in which the mechanism is in action, that is to say when it is desired to terminate the casting of the lines or letters automatically. For normal composing, the operator pulls the knob 195 towards him, he slightly turns it to the right and releases it. By this movement, he releases the lever 191 which is placed under the repetition lever 152 (Fig. 11) and places it in the position shown in Fig. 12. By turning the knob to the right, he moves, through the medium of the rod 188 and link 186, the lever 185 to the position shown in dotted lines in Fig. 9. By releasing the knob, the hook 196 engages with a notch 196^a provided in the support 190 and remains engaged therein under the pressure 40 of the spring 197. In this position, the levers 183 and 184 are located sufficiently far away, one from lever 179, and the other from roller 184 in order that the movement of the cam shaft and composing stick should have no action on said 45 levers 183 and 184. For resetting the device in action, the operator turns the knob 195 to the right for releasing the hook 196 from the notch 196^a; under the action of the spring 197, the rod 188 slides and the levers again return under 50 the action of their own weight, to the position corresponding to the automatic disengagements.

55 It will be remembered that in the "Rototype" machine, the composing stick 148 receives the cast type, ejected from the mould one after the other, until the line is entirely terminated. The type 224 are held in the composing stick, on the one hand, by two lower pawls 225 arranged in the composing stick and, on the other hand, by a movable head 226 acting as an upper pawl; at 60 the end of the line, this movable head 226 moves the cast line towards the galley and returns to its original position (Figs. 13 to 15).

65 Said movable head 226 is set in movement through the medium of a lever 227 controlled by 70 a cam 228 which, at the end of each line, is

caused to rotate through the action of a pawl 5 of drum 4.

Each of the cast lines has its own justification; the element which transmits to the mould the measurement of the spaces of the corresponding line is withdrawn at the end of the line and replaced by another similar element, but which transmits the measurement of the spaces corresponding to the next line. In this machine, if it is desired to compose or set lines divided 10 into a plurality of columns and to give to each column an exact length, each portion of the line, that is to say each column element, is considered as an independent line, having its own justification and it is composed accordingly. 15

It is known that the "Rototype" machine is provided with a counter of the thicknesses of the letters and with a counter of the spaces; at the end of each line formed on the keyboard and recorded on the drum 4, the depression of a key 20 automatically determines the justification; the latter consists in the measurement, in the line composed, of the gap remaining to be filled by the spaces, and in the division of this gap by the number of spaces contained in the line and recorded on the space counter. The result of this automatic operation is transmitted on the elements which control the opening of the mould for the casting of the spaces, during the casting 25 of the corresponding line.

The central rod which, at the end of the line composed, by moving towards the rod of the counter measures the gap to be filled up in this same line, is following the invention replaced by as many rods as there are columns in the table. 30

For four columns, for instance, a small carriage 229 (Figs. 16 and 17) is provided with four holes in which are secured four rods 98^a-98^d of different lengths. The carriage takes the place of the simple rod used for the composing of non-divided lines. The lengths of the four rods are adjusted according to the width of the columns to be composed. They are such that the free end of the first rod 98^a is, before composing, placed, relatively to the central rod of the 40 counter, at a distance corresponding to the width of the first column, the end of the second rod at a distance corresponding to the width of the two first columns, etc.; the end of the last rod 98^d is placed at a distance corresponding to the total 45 width of the four columns, that is to say to the total width of the table.

The carriage 229 can be moved in a slide 230, in order that the suitable rod should be opposite the central rod of the counter. This displacement can be effected either by hand, or automatically. In the example illustrated, a hand displacement is provided. A ball 231, pushed by a spring against the wall of carriage 229, ensures the position of the latter. At the end of a 50 column, the carriage is pushed from one position to the next, and, at the end of a line, it is restored to its original position. These rods 98 might also be arranged on a drum which would be caused to rotate for passing from one position 55 to the other.

Under a flexible bar of the counter is held a strip of paper on which are marked the widths of the columns, so that the index secured on the central rod, moving at each letter formed on the 60 keyboard, indicates that the end of the first column is nearly reached. The operator then depresses on the line end key as in ordinary composing.

The gap to be filled up in this first column 75

is measured through the medium of the rod 98^a of carriage 229; the measurement of the spaces for this first column is sent to the mould by the corresponding transmission element. The operator has previously moved down the lever controlling the return to zero of the counter of the thicknesses of the type formed, so that by depressing the line end key this counter is not moved backward.

10 The operator, before moving the rod 98^a which has served for the justification of the first column, moves the central rod towards said rod 98^a for the addition of the thicknesses of the type, in order that it should indicate the total length 15 composed. He then pushes the carriage 229 so that the second rod 98^b should come in front of this central rod of the counter.

He composes the second column, depresses the line end key, moves the central rod towards the 20 second rod 98^b, causes the third rod to move forward, composes the third column, etc.

25 After justification of the fourth column, the operator pulls the carriage 229 with its four rods to its starting position and immediately begins the composing of the second line.

It is necessary after casting each line section (column) that the head 226 should effect its movement for driving the type, that is to say without removing the type from the composing 30 stick, so that the type of one column should be added to those of the preceding column until the line is complete. When the line is complete, it must be pushed towards the galley by the head 226, and this automatically, whatever may 35 be the number of columns composing it.

For that purpose, the support of the composing stick carries a pair of pinions 232 and 233 mounted on a common shaft 233^a, provided at its other end with a knob 234 for rotating it by hand. This shaft 233^a, and the members it carries, is mounted in a bearing 235 secured on the rear part of the support of the composing stick, so that it can be very rapidly removed or replaced in position. In the bearing 235 is moreover provided a spring box 236 in which is arranged a piston 237 entering between the teeth of the pinion 233 and which holds the latter in the position in which it has been placed either by hand at the beginning of the composing, or 50 mechanically for continuing the operation.

In the lower part of the support 148 of the composing stick is arranged a rod 238 carrying a pawl at each end. The left-hand pawl 239 is inserted between the teeth of the pinion 233; 55 when the rod 238 is pushed towards the left, by the lever 227, under the action of the cam 228, this pawl moves pinion 233 to the extent of one tooth and of one tooth only. The movement of lever 227 being sufficient for transporting the type line cast is of great amplitude, but the rod 238 is pushed to the strictly necessary extent, owing to the second pawl 240 which sufficiently projects to be engaged by lever 227, but the left-hand end of which, lowered by a spring (not 60 shown) encounters a small incline 242 of the support, which lifts it, this releasing its right-hand end from the lever after a necessary and sufficient displacement of the rod 238.

A two-arm lever 243 is rockably mounted on 70 support 148; its left-hand end forming a nose 243^a is inserted between the teeth of pinion 232; by the rotation of pinion 233, also keyed on shaft 233^a, the arm of this lever resting on the head 226 is lowered.

75 Above the lever 243 is hung a finger 244 urged

by a spring 245. As long as lever 243 remains in its position of rest, these members are in the position shown in Fig. 13. When the pinion 233 is rotated to the extent of one tooth by pawl 239, the right-hand arm of lever 243 lowers, thus 5 lowering the head 226. The finger 244 pulled towards the left by the spring 245 moves out of the notch of lever 243 in which it was inserted and prevents the right-hand arm of lever 243 from rising to its original position.

The right-hand end of the pivotally mounted head 226 is lifted and when it is actuated by lever 227, it passes over the cast type, without moving them. This lever has therefore effected its idle movement towards the left, and this 15 every time a portion of the line (column element) is terminated. Thus, the cast column element or elements remain in the composing stick to the last one.

For each portion of the line (column) the 20 pinion 232 rotates to the extent of one tooth; for the end of the line (after the last column), the nose of lever 243 does not encounter any tooth owing to a gap in the pinion 232; notwithstanding the rotation of pinion 232, the position 25 of lever 243 is then not changed; the head 226 is not moved either and, remaining behind the type 224 which are in the composing stick, it moves the said type towards the left upon movement of lever 227.

30 In the example shown in Fig. 13, the pinion 232 has twelve teeth and each fourth tooth is missing. For composing lines of three columns, each third tooth would be missing, for lines of two columns, each second tooth would be missing, for five columns, use would be made of a pinion having ten teeth (number divisible by five). The pinion 233 having no tooth missing and rotating at each impulse of the pawl 239 remains always the same.

What I claim as my invention and desire to 40 secure by Letters Patent is:—

1. In a machine for casting and setting movable type, a frame carrying a plurality of matrix blocks, means for automatically putting, by 45 a rotation of the entire group of blocks, one or the other of the latter in working position opposite the mould, and means for automatically starting this group of blocks.

2. In a machine for casting and setting movable type, an outer frame in which a plurality of 50 shafts are arranged, matrix blocks on these shafts, two discs carrying these blocks, a central shaft having a plurality of sides, bracing both discs and serving as a bearing of the blocks during casting of the type, two other discs carried by said central shaft, one of which serves for causing the group of matrix blocks to move forward and the other serving to hold the matrix blocks in exact position in front of the mould. 55

3. In a machine for casting and setting movable type as claimed in claim 2, a lever rotating about said central shaft and provided, at its end, with a pawl entering a recess of the disc serving to move forward the group of matrix blocks, a lever controlled by a crank acting on the said pawl for causing said disc to rotate through a fraction of a revolution corresponding to the passage from one matrix block to the other. 60

4. In a machine for casting and setting movable type as claimed in claim 2, a locking lever 70 extending in the notches of the disc serving to hold the matrix block in exact position in front of the mould, a lever for controlling this locking 75

lever and which releases it in order that the group of matrix blocks can effect a movement of rotation within the matrix-carrying frame.

5. In a machine for casting and setting movable type as claimed in claim 4, a disc secured on one of those carrying the shafts of the matrix blocks, notches in this disc in which is engaged a lever controlled by the locking lever so as to be released at the time the movement of rotation must take place for engaging it a little before the end of this movement in order to absorb the shock which takes place by the sudden stoppage of the whole at each revolution.

6. In a machine for casting and setting movable type, a system of lever rocking owing to the rotation of an eccentric through a revolution, which rotation is allowed by the simple depression of a key of the keyboard in order to actuate the lever of the operations of each line end.

20 7. In a machine for casting and setting movable type as claimed in claim 6, levers set in action, upon rotation of said eccentric for holding stationary the screw capable of clamping the central shaft of the thickness counter, so as to prevent its clamping during the return to zero of the thickness counter and of the matrices until this central shaft and the carriage of the thickness counter have completely moved backward.

8. In a machine for casting and setting movable type, a shutter for correcting the position of the pawls of the drum which project insufficiently.

9. In a machine for casting and setting movable type, means for the automatic actuation of the lever causing the rotation of the drum, on the one hand, in a line, by the effect of the rotation of the shaft controlling the casting and setting of the type and, on the other hand, at the end of a line by the effect of the composing stick system, so that it becomes possible to cast

type previously automatically recorded in a continuous manner and without depression of any key on the keyboard.

10. In a machine for casting and setting movable type, as claimed in claim 9, means for rendering inoperative the mechanisms for this automatic actuation upon rotation of the drum by forming letters on the keyboard. 5

11. In a machine for casting and setting movable type, means which at the end of the composing of the justified column element, prevent the type of this element being evacuated from the composing-stick towards the galley, except if this element is the last in the line, in which case the entire line is evacuated. 15

12. In a machine for casting and setting movable type, as claimed in claim 11, a toothed pinion having regularly distributed gaps in its teeth, so that at each end of a column element the passing of a tooth ensures the putting out of action 20 of the member evacuating the type towards the galley, and that the passing of a gap, at the end of a line, allows, on the contrary, this evacuation.

13. A machine for casting and setting movable type, in which the rod of the counter of the width of the type is not reset to zero after justification of each line section, and in which a carriage carrying as many rods as there are columns can be moved in such a manner as to bring these rods opposite those of the counter, the lengths of these rods being such that the end of the first one is, before composing, placed relatively to the central rod of the counter at a distance corresponding to the width of the first column, the end of the second rod at a distance corresponding to the width of the two first columns, and so on. 25 30 35
